(57) **CLAIM**

The ornamental design of a seat back bag or portion thereof, as shown and described.

DESCRIPTION

FIG. 1 is a perspective view of a seat back bag in a first orientation in accordance with another embodiment of the present design;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1;

FIG. 7 is a bottom plan view of FIG. 1;

FIG. 8 is a perspective view of a seat back bag in a second orientation in accordance with another embodiment of the present design;

FIG. 9 is a front elevation view of FIG. 8;

FIG. 10 is a rear elevation view of FIG. 8;

FIG. 11 is a left side elevation view of FIG. 8;

FIG. 12 is a right side elevation view of FIG. 8;

FIG. 13 is a top plan view of FIG. 8; and,

FIG. 14 is a bottom plan view of FIG. 8.

The features shown in broken lines in the various figures, which may include structural features, such as threading, form no part of the claimed design. The shading shows contours, surfaces, or recesses of the present invention. The article is not limited to the scale shown herein, as indicated in the title, the article of manufacture to which the ornamental design has been applied is a seat back bag, portion thereof or a novelty item.
